UNITED STATES PATENT OFFICE

CHARLES S. BURTON, OF OAK PARK, ILLINOIS

VACUUM TANK

Application filed April 22, 1929. Serial No. 356,935.

The purpose of this invention is to provide an improved construction in a vacuum tank adapted to obviate a defect which characterizes vacuum tanks in common use deriving from the liability of the atmosphere inlet valve to be prevented from effective seating by reason of foreign matter, dust, etc., in the atmosphere becoming lodged on or adherent to the valve seat and seating face of the valve.

A specific purpose of the invention is to obviate this defect in a construction designed to facilitate dispensing with a valve to control the suction connection by providing means for counterbalancing the suction stress on the atmosphere inlet valve, so that the atmosphere inlet port may be made large enough to make negligible the vacuum in the chamber resulting from continuity of suction when the atmosphere valve is open. The invention consists in the elements and features of construction shown and described as indicated in the claims.

In the drawings:

Figure 1 is a vertical section of a vacuum tank embodying this invention.

Figure 2 is a top plan view of the same.

Figure 3 is a detail portion of the structure shown in Figure 1 on an enlarged scale.

Figure 4 is a view similar to Figure 1 showing a modification.

Figure 5 is a top plan view of the form shown in Figure 4.

Figure 6 is a view similar to Figures 1 and 4 showing a modification following that shown in Figure 4 with the omission of the fuel pocket for flushing the air inlet valve which is contained in the previous forms.

Figure 7 is a top plan view of the form shown in Figure 6.

Referring to the drawings in detail, in all the forms shown the vacuum chamber is seen at A. The outer or main body member constituting the customary fuel reserve chamber is indicated at B. C is a cap which closes both chambers at the top and secures them together by means of an annular stamping, D, formed zig-zag in a radial section, lapping and soldering outside the body member, B, and lapping inside the peripheral flange,

10 of the cap, C, under a marginal flange, 11, of the chamber, A. The three parts, viz., the annular stamping, D, which is permanently attached to the chamber, A, the chamber, B, and the cap, C, are separably secured together by bolts, 12, with a suitable packing gasket, 13, interposed for liquid-tight junction between the cap, C, and the vacuum chamber, B. Fuel inlet fitting is seen at F. The fuel outlet fitting is seen at G, controlled by valve, g, and a suction connecting fitting is seen at E, having a restricted suction port, e. Atmosphere vent of the chamber, B, is seen at H.

Referring to the form shown in Figure 1, the cap, C, has an aperture, 20, encompassed by an interiorly projecting flange, 21, constituting the atmosphere inlet port, and having the atmosphere inlet controlling valve, 22, seating on the edge of the flange, 21. The fuel inlet connection is located immediately adjacent to the inwardly flanged aperture, 20, and said flanged aperture and said fuel inlet connection are encompassed within the tank by a pocket member, 25, secured to the under side of the cap, C, said pocket having an overflow aperture, 26, at a level above the seat of the valve, 22.

From this construction it results that the fuel drawn into the chamber from the fuel source by suction due to vacuum in the chamber is discharged into the pocket and fills the same above the level of the valve seat before it overflows through the overflow aperture, 26, for filling the vacuum chamber, A. The atmosphere inlet valve is thus certain to be wetted and flushed by the incoming liquid fuel in a manner which will clear it of any solid material, dust particles, and the like, which may enter with the atmosphere.

In the construction shown in Figure 1, the atmosphere inlet valve, 22, is arranged to be seated interiorly with respect to the chamber, A, so that the suction due to vacuum in the chamber tends to hold it open. For counterbalancing the suction action on the valve, a portion of the wall of the chamber, A, consists of a diaphragm, K, closing an aperture, 30, in the cap, C, the diaphragm being mounted on the outer side of the cap by

clamping ring, 31, and the diaphragm being provided with a stem, 34, clamped at the center of the diaphragm and extending both above and below the diaphragm, that is, outside and inside the chamber.

5 The valve, 22, has a stem, 23, which extends out through the atmosphere inlet and obtains guidance in a spider, 24, mounted on the outer side of the cap. The valve and diaphragm stems, 23 and 34, are operatively connected by a lever, 36, fulcrumed at 32 on a bracket, 33, mounted upon the upper side of the cap, C, and by this lever connection it will be seen that the suction pull on the diaphragm is opposed to the suction pull on the valve, and the valve and diaphragm having approximately the same effective areas, the two arms of the lever being approximately equal, the suction is substantially counterbalanced. Within 10 the chamber, A, the lower end of the diaphragm stem, 34, is connected to a lever, 35, intermediate the ends of the latter, said lever being fulcrumed at one end on a bracket, 35^a, carried by the cap, C, and depending therefrom. To the opposite end of the lever there is pivotally connected for depending therefrom, a float guide stem, 37, on which there is mounted for sliding between upper and lower stops, 38 and 39, a float, 40, the float guide stem, 37, being itself guided at its lower end in the spider, 41, provided at the fuel inlet leading to the fitting, G. The weight of the lever, 35, and stem, 37, it will be observed, operates on the diaphragm in the direction 15 of the suction, creating a slight overbalance of force for seating the valve.

The operation of this construction may be understood from the foregoing description to the intent that starting with the apparatus empty and with the vacuum chamber connected by the fitting, E, with a source of suction, as, with the intake manifold of the engine, the atmosphere valve, 22, will be normally closed, not only by the overbalance due 20 to the weight of the lever, 35, and the float stem, 37, but additionally by the operation of the weight of the float, 40, which will be resting upon the lower stop, 39. The vacuum resulting in the chamber, A, will cause fuel to be lifted from the fuel source and discharged by way of the fitting, F, into the trap, 25, filling the same to a depth for submerging the valve, 22, and then overflowing by the port 26, to fill the chamber, A. Upon 25 the chamber being filled to a depth, causing the float to be lifted into contact with the upper stop, 38, the float will be there halted until the further rise of liquid level submerges it so as to develop its buoyant value to the slight degree necessary to overcome the weight of the lever and connected stems, and open the atmosphere valve which, it will be remembered, is substantially balanced as to the suction and independently of the weight 30 of the lever, 35, and float stem, 37, the slight

hydrostatic pressure of the liquid content of the trap, 25, tending to hold it on its seat being, however, also taken into account in dimensioning the valve and diaphragm, so that slight buoyant effort of the float beyond what is necessary to pick up the weight of the level of the lever and stems will open the valve. 70

Upon the valve being thus opened, admitting atmospheric pressure through the atmosphere port which is very large relatively to the suction port, e, the vacuum will be substantially relieved, permitting the liquid to be discharged through the outlet fitting, G, into the reserve chamber, A, and lowering the float until it is again lodged on the lower stop, 39. The atmosphere valve being open, admits the atmospheric pressure so freely that the suction action on the diaphragm is almost negligible; but upon the descent of the float away from the upper stop, 38, the slight excess indicated in Figure 1 of the area of the atmosphere valve over the effective area of the diaphragm may be adapted to cause the atmosphere valve to remain open until the liquid level falling still further after the float becomes lodged on the lower stop, 39, causes the float to be de-submerged and to operate by its weight for pulling down the long arm of the lever, 35, which will cause the atmosphere valve to be seated, terminating the discharge of the liquid and restoring the initial conditions under which the continuous suction through the suction port, e, will restore the condition of vacuum in the chamber and cause the same to be refilled and the entire cycle of operations to be repeated. 90

It is, however, considered preferable not to rely entirely on the slight excess area of the valve, 22, over the effective area of the diaphragm for causing the valve to remain open while the float is descending; and this excess area may be dispensed with in view of the construction shown in Figures 1 and 2 as follows:— 105

The lever, 36, has extending down from its pivot a short arm, 36^a, between whose lower end and the foot of the bracket, 33, there is interposed a light compression spring, 36^b, which operates for light snap action in a familiar and well understood manner, to ensure the completion of the opening movement of the valve, 22, which will be begun by the buoyant effort of the float, 40, upon its encounter with the upper stop, 38. But this construction is designed more particularly to ensure the valve remaining open when the subsidence of the liquid level lowers the float away from the stop, 38, leaving the valve subject to the hydrostatic pressure due to the slight submergence of the valve in the liquid content of the trap pocket, 25, plus the weight of the stems, 34 and 37, and the lever, 35, tending to close it. 115

This snap action it will be seen is adapted to operate similarly for ensuring that the 120

valve, 22, remains closed when the float rises off the lower stop, 39, while the chamber is filling, though its service for this purpose is not in fact required, since at that stage the overbalance provided by the weight of the stems and lever as pointed out, adequately ensures the seating of the valve until opened by the buoyant effort of the float encountering the stop, 38.

The presence of the snap action makes necessary a slight increase in the size of the float both for increase of buoyancy and for increase of weight; but this increase is very slight and warranted by the greater certainty which is thereby afforded by the proper operation in the float-descending phase of the cycle of operation of the apparatus.

Referring to the modified form shown in Figures 4 and 5, in which the corresponding and substantially identical parts are indicated by the same reference characters as in Figures 1, 2 and 3:—The modification consists in arranging the atmosphere inlet valve for opening outwardly so as to be held seated by the suction, the connection with the diaphragm being arranged as in the form shown in Figure 1 for opposing the suction-caused action of the valve, and substantially counterbalancing these opposed actions. This change necessitates a change in the float connection, which must be arranged to cause the buoyant effort of the float to operate inwardly on the diaphragm and outwardly on the valve instead of outwardly on the diaphragm and inwardly on the valve as in Figure 4.

For this difference of operation, the flange, 21^x, corresponding to the flange, 21, of Figure 1, is reflexed at its inner end so as to project outwardly, as seen at 21^y, so that the valve, 22, may seat exteriorly with respect to the port, 20, bounded by the reverse flange, 21^y; and the lever 36^x, corresponding to the lever, 36, of Figure 1, is fulcrumed midway between its ends, as seen at 36^x, on a bracket, 33^x, and has the diaphragm stem, 34, connected to it at one end, as seen at 36^w.

In other respects the construction shown in Figures 4 and 5 is the same as that shown in Figures 1 and 2, except that it is not necessary to provide anything corresponding to the snap action shown in Figure 1 for ensuring the valve remaining open while the float is descending, because when the valve is opened by the buoyant effort of the float, the suction pull on the valve for seating it is almost entirely lost, whereas the diaphragm is still subject to suction pull inwardly due to the remnant of vacuum which will exist in the chamber with the atmosphere valve wide open, by reason of the uninterrupted suction operating through the restricted but always open suction port, e; and this suction pull on the diaphragm will be rendered adequate to offset and exceed the weight of the valve stems and lever, 35, and hold the valve open,

by making the effective area of the diaphragm slightly greater than that of the valve as indicated in Figure 4.

In this form it is convenient to provide adjustment to compensate for unavoidable variation in the weight and buoyant value of different floats, and similar slight unavoidable difference in the weight of the stems and lever connections, to ensure the proper and necessary and not excessive overbalance for seating the valve, 22; and such provision is shown consisting in extending the lever, 15, to the right of its connection to the valve stem, 23, and threading it at such extended part for receiving a small weight, 50, which is screwed onto it and may be adjusted to greater or less distance from the fulcrum of the lever and secured in adjusted position by a set screw, 51.

In the form shown in Figures 6 and 7, the pocket for trapping liquid to flush the atmosphere inlet valve and its seat is omitted. This omission dispenses with the need of the inwardly projecting flange which is necessary to provide the seat for the valve within the trap pocket which is shown in the previous forms; and accordingly the atmosphere inlet port, 20^x, is formed in the flat surface of the cap plate, C. The omission of the trap pocket dispenses with the necessity of connecting the float with the atmosphere valve and the diaphragm connecting lever by way of the diaphragm stem, as in the previous figures; and the float stem, 37, is accordingly connected directly to the atmosphere valve, 22, and extended thereabove for connection with the lever, 36, by which the diaphragm and valve are connected for opposing the suction action on the diaphragm to the suction action on the valve.

The operation of this form is in all respects the same as that of the form shown in Figures 4 and 5, except as to the flushing of the atmosphere valve by the liquid trapped in the pocket.

This application is a continuation in part of my pending application Serial No. 341,585, filed February 21, 1929, from which certain of the following claims borrowed with a view to abandoning said pending application and covering the subject matter in this application.

I claim:

1. A construction for the purpose indicated comprising a chamber having connection with a source of suction for producing partial vacuum in the chamber, said chamber having a movable wall member exteriorly exposed to atmospheric pressure and a liquid inlet, a liquid outlet and an atmosphere inlet port; a valve controlling the atmosphere inlet port arranged with respect to said port for opening and closing by movement in the direction of air flow through the port, whereby suction in the chamber tends to move the valve

- relatively to its seat; operating connections between the movable wall member and the valve arranged for opposing to each other the suction action on the valve and wall member respectively, and means operated by a change of level of the liquid content of the chamber for opening and closing the valve at predetermined high and low levels respectively of said liquid content.
10. In the construction defined in claim 1, the movable wall member and the valve and the operating connections between them being dimensioned and arranged for substantially equalizing the opposed actions, and 15 auxiliary means for relatively slight pressure on the valve in the direction for seating it.
11. In the construction defined in claim 1, the operating connections between the movable wall member and the valve, being mounted outside the chamber.
12. In the construction defined in claim 1, the operating connections between the movable wall member and the valve comprising a lever of the first class, the means operated by change of liquid level comprising a float, and means by which it is suspended from the arm of said first class lever which is connected with the movable wall member.
13. In the construction defined in claim 1, the operating connections between the movable wall member and the valve comprising a lever of the first class, the means operated by change of liquid level comprising a float, 25 and means by which it is suspended from the arm of said first class lever which is connected with the movable wall member, said suspending means comprising a rod on which the float is arranged to be slid up and down 30 by the changes of liquid level, and stops on said rod positioned for encounter by the float at predetermined limits of said up and down sliding movement.
14. In the construction defined in claim 1, 35 the movable wall member being a flexible diaphragm, and the operating connections between the same and the valve being a lever of the first class.
15. In the construction defined in claim 1, 40 the operating connections between the valve and the movable wall member being mounted exteriorly of the vacuum chamber.
16. An apparatus for the purpose indicated comprising in combination with a vacuum chamber having suction connection, fuel inlet and fuel outlet, and having an atmosphere inlet port and a valve controlling said port, with means in the chamber for opening and closing said valve operated by change of level 45 of the liquid content of the chamber, the chamber having in the upper part a pocket adapted to hold liquid and arranged to overflow into the chamber, the fuel inlet connection being arranged for delivering the fuel 50 into said pocket, and the atmosphere port

being arranged to open in said pocket below the overflow level thereof; whereby the valve seat and seating face of the valve are flushed and kept moistened by the liquid fuel.

9. In an apparatus for the purpose indicated comprising in combination with a vacuum chamber having fuel inlet, fuel outlet, suction connection and atmosphere inlet, a valve controlling the atmosphere inlet, the chamber having a limited portion of its wall which is exteriorly exposed to atmospheric pressure movable inwardly and outwardly without opening the wall, and operating connections between the atmosphere inlet valve and said movable wall portion arranged to oppose the suction stress on the valve due to vacuum in the chamber to the suction stress on the movable wall chamber due to the same cause, the chamber having in the upper part a pocket adapted to hold liquid and arranged to overflow into the chamber, the fuel inlet connection being arranged for delivering the fuel into said pocket, and the atmosphere inlet port being arranged to open in said pocket below the overflow level thereof.

10. In an apparatus for the purpose indicated, in combination with a vacuum chamber having fuel inlet, fuel outlet, and suction connection, an atmosphere inlet and a valve controlling said inlet seating interiorly of the chamber, whereby suction in the chamber tends to unseat it, the chamber having a limited part of its wall movable inwardly and outwardly with respect to the chamber without opening the wall, and operating connections between the atmosphere inlet controlling valve and the movable wall member arranged to oppose the suction stress on said movable wall member to the suction stress on the valve, the chamber having in the upper part a pocket adapted to hold liquid and arranged to overflow into the chamber, the fuel inlet connection being arranged for delivering the fuel into said pocket, and the atmosphere inlet port being arranged to open in said pocket below the overflow level thereof, whereby the valve seat and seating face of the valve are flushed and kept moistened by the incoming liquid fuel.

11. In the construction defined in claim 8, the pocket having its overflow above the high liquid level of the chamber, whereby the atmosphere inlet port and valve seat may be at all times above any liquid content of the chamber except that of the pocket.

12. In the construction defined in claim 8, the chamber wall having an inwardly projecting part in which the atmosphere inlet port is located, the pocket being arranged encompassing said inwardly projecting part.

13. In the construction defined in claim 8, the atmosphere inlet port being formed in the top of the chamber and the pocket being suspended from the chamber top under and encompassing the inlet,

14. In the construction defined in claim 8, the top of the chamber having an interiorly flanged opening affording access of atmospheric pressure to the chamber, the atmosphere inlet valve being arranged to seat on the flange, the pocket being suspended from the top of the chamber encompassing the flange and having its overflow slightly about the level of the valve seat on the flange, valve-operating connections extending out through the flanged opening and comprising a member which extends back into the tank for connection with the valve-operating means.
15. In the construction defined in claim 8, the chamber wall having an interiorly flanged aperture of which the flange protrudes into the pocket and affords seat for the inlet valve, the valve operating connections comprising a stem of the valve which extends out through said flanged aperture and comprising also a member which extends back into the chamber for connection with the valve operating means.
16. An apparatus for the purpose indicated comprising in combination with a vacuum chamber having suction connection, fuel inlet and fuel outlet, and having an additional opening, and encompassing said additional opening an interiorly projecting annulus whose aperture constitutes an atmosphere inlet port; a valve controlling said port, and means in the chamber for opening and closing said valve arranged to be operated by change of level of the liquid content of the chamber, the fuel inlet connection being arranged to deliver the fuel in such relation to said interiorly projecting annulus as to flush the seat of said valve.
17. The construction defined in claim 16 having a pocket formed on the wall of the chamber, the atmosphere inlet port and valve seat being in said pocket and the fuel inlet connection being arranged to discharge in said pocket.
18. In the construction defined in claim 16, the annulus and opening which it encompasses being appurtenant to the top wall of the chamber, and the arrangement for causing the inflowing fuel to flush the valve seat consisting in a pocket carried by said top wall surrounding the annulus and the discharge of the fuel inlet connection.
19. An apparatus for the purpose indicated comprising in combination with a vacuum chamber having a suction connection, fuel inlet and fuel outlet, and having an atmosphere inlet port, a valve controlling said atmosphere inlet port with means in the chamber for opening and closing said valve operating by change of liquid level of the liquid content of the chamber, the chamber having in the upper part a pocket arranged to receive liquid and to discharge into the chamber, the fuel inlet connection being arranged for delivering fuel into said pocket, the atmosphere port being arranged to open in said pocket at a lower level than said fuel inlet.
20. An apparatus for the purpose indicated comprising in combination with a vacuum chamber having a suction connection, fuel inlet and fuel outlet, and having an atmosphere inlet port, a valve controlling said atmosphere inlet port with means in the chamber for opening and closing said valve operated by change of level of the liquid content of the chamber, the chamber having at the upper part a pocket adapted to receive liquid and arranged to overflow into said chamber, the fuel inlet connection being arranged for delivering fuel into said pocket, and the atmosphere inlet port being arranged to open in said pocket below the overflow level thereof.
- In testimony whereof, I have hereunto set my hand at Chicago, Illinois, this 15th day of April, 1929.
- CHARLES S. BURTON.
